UNITED STATES PATENT OFFICE

92,223

DESIGN FOR A GLOVE

Helen Ruth Ziegler, Los Angeles, Calif.

Application February 20, 1934, Serial No. 50,788

Term of patent 7 years

To all whom it may concern:

Be it known that I, HELEN RUTH ZIEGLER, a citizen of the United States, residing at Los Angeles, in the county of Los Angeles and State of California, have invented a new, original, and ornamental Design for Gloves, of which the following is a specification, reference being had to the accompanying drawing, forming part thereof. The figure is a perspective view of a glove, showing my new design.

I claim:

The ornamental design for a glove, as shown.

HELEN RUTH ZIEGLER.
